UNITED STATES PATENT OFFICE.

EDGAR BOLHÁR VON NORDENKAMPF, OF VIENNA, AUSTRIA-HUNGARY.

MOSAIC COVERING FOR WALLS, COLUMNS, AND THE LIKE.

1,028,058.

Specification of Letters Patent.

Patented May 28, 1912.

Application filed May 14, 1910. Serial No. 561,407.

To all whom it may concern:

Be it known that I, EDGAR BOLHÁR VON NORDENKAMPF, a subject of the Emperor of Austria-Hungary, residing at 5 Schellein-gasse, in the city of Vienna, Empire of Austria-Hungary, have invented certain new and useful Improvements in Mosaic Coverings for Walls, Columns, and the Like, of which the following is a specification.

10 The present invention has for its object a mosaic-construction for walls, columns and the like, and more especially for those formed from reinforced concrete, which invention consists of a plate having openings 15 and forming a frame or foundation, on which the mosaic stones are fastened by means of projecting pieces of button shape provided on the back of the mosaic stones and which engage or lock in the openings 20 in the plate.

In the drawings several applications of the invention are shown.

Figure 1 is a view of a mosaic wall constructed according to the present invention. 25 Fig. 2 a section on the line A—B of Fig. 1. Fig. 3 represents a single stone showing the structural parts. Fig. 4 shows a column in cross section. Fig. 5 shows a reinforced concrete wall in section with the plate on 30 the outside. Fig. 6 is a similar view showing the plate embedded in the wall, and Fig. 7 represents a square column in perspective.

The mosaic construction consists pref-35 erably of a sheet metal plate *a* which contains the openings *b* apportioned over the plate in accordance with the desired ar-40 rangeement of the stones of the mosaic. Each stone *c* is provided on its back with 45 a button shaped piece *d* which serves for securing the stone to the plate. The open-50 ings *b* extend downward in the form of slots *f* in which the button pieces of the stones *c* are inserted, which hold the stones firmly 55 against the plate. The openings *b* of the plate *a* can of course have many different shapes, in so far as they serve the function of holding the mosaic stones firmly against the plate and afford a quick means for fas-60 tening and detaching the stones.

As the plate for holding the stones pos-65 sses sufficient firmness and stiffness itself to form a secure and reliable support, the plate can be used as a screen or a frame for 70 fancy panes for windows and the like. The

button shaped pieces of the stones by means of suitable ornamentation may themselves form mosaic stones, so that the back also of such a mosaic wall can be very tastefully worked up and so not only can a varied or-60 namentation of the front side be attained but also of the back of the wall.

By the use of half stones *g* (Fig. 1) and quarter stones *h* and in addition half stones *i* and quarter stones *j* formed by dividing 65 the whole stones along a diagonal, the va-70 riety of the patterns to be made is increased to a great extent.

By securing the stones to the plate by means of a button shaped piece on the back 70 of the stones, each stone is automatically centered and firmly attached so that even when the mosaic wall is placed horizontally or inclined the button shaped pieces will 75 not be easily damaged or broken off.

The use of a metal plate as a foundation for the stones is especially advantageous, in reinforced concrete construction because the metal plate embedded in the mass of concrete forms itself a supporting element of 80 the concrete construction.

By placing two mosaic walls opposite each other (Fig. 5) which are connected together by means of iron rods *k* a hollow form is 85 constructed which can be filled with con-crete in order to obtain a concrete wall. It is therefore not necessary to provide special sides for the hollow form as the sides are provided by the metal plates of the mosaic construction. In a like manner is it possible 90 to construct, polygonal or round columns (Figs. 4 and 7) in which cases the plates are supported by embedding iron rods 1 or the like in the mass of concrete.

The mosaic construction according to the 95 present invention can however easily be connected to a concrete wall (Fig. 6) by ar-100 ranging the plate with the stones before in-105 troducing the mass of concrete in a suitable manner into the hollow form.

The above described form of the mosaic stones makes the construction possible for all adaptable materials, such as colored clay, glass or the like, and allows of an expedi-tious arranging of the stones.

It is to be understood that slight changes in the form, proportion and minor details of construction may be resorted to without sac-110 rificing any of the advantages or departing from the spirit of the invention.

Having fully described my invention, what I claim is:

1. In a concrete construction having a mosaic surface, the combination of a frame provided with a plurality of apertures; a plurality of blocks having undercut extensions passing through said apertures and projecting beyond said frame; and a filling of plastic material contacting with said frame and surrounding the projecting ends of said undercut extensions, substantially as described.
2. In a concrete construction having a mosaic surface, the combination of a frame provided with a plurality of apertures having locking extensions; a plurality of blocks having undercut extensions passing through said apertures interlocking with the extensions of said apertures and projecting beyond said frame; and a filling of plastic material contacting with said frame and surrounding the projecting ends of said undercut extensions, substantially as described.
3. In a concrete construction having a mosaic surface, the combination of a frame provided with a plurality of T-shaped aper-

tures; a plurality of blocks having undercut T-shaped extensions passing through said apertures interlocking with the same and projecting beyond said frame; and a filling of plastic material contacting with said frame and surrounding the T-shaped projecting ends of said undercut extensions, substantially as described.

4. The method of producing a concrete construction having a mosaic surface, which consists in providing a frame with a plurality of apertures; passing the undercut extensions of a plurality of closely fitting blocks through said apertures and beyond said frame; and placing a plastic material in contact with said plate and around said undercut projecting extensions to hold said blocks in place, substantially as described.

In testimony whereof I have affixed my signature in presence of two witnesses.

EDGAR BOLHÁR VON NORDENKAMPF.
